ATTORNEYS.

Patented Dec. 6, 1927.

UNITED STATES PATENT OFFICE.

THOMAS CLARENCE HEISEY, OF NEWARK, OHIO, ASSIGNOR TO A. H. HEISEY & COMPANY, OF NEWARK, OHIO, A PARTNERSHIP.

DESIGN FOR A CANDLESTICK.

Application filed January 7, 1927. Serial No. 20,299. Term of patent 14 years.

To all whom it may concern:

Be it known that I, THOMAS CLARENCE HEISEY, a citizen of the United States, residing at Newark, in the county of Licking and State of Ohio, have invented a new, original, and ornamental Design for a Candlestick, of which the following is the specification, reference being had to the accompanying drawing forming a part hereof.

The figure is a perspective view of a candlestick, showing my new design.

I claim:

The ornamental design for a candlestick, as shown.

THOMAS CLARENCE HEISEY.
